UNITED STATES PATENT OFFICE

HARRY C. FOSTER, OF CONNERSVILLE, INDIANA, ASSIGNOR TO INDIANA LAMP CORPORATION, OF CONNERSVILLE, INDIANA, A CORPORATION

LAMP CONSTRUCTION

Application filed January 30, 1930. Serial No. 424,472.

This invention relates to a lamp construction particularly for use as a tail and stop lamp for automobiles. More particularly it relates to a type of lamp in which a stop warning is given by lighting a lamp bulb placed behind a stencil in which is cut the word "Stop" or other warning signal.

The principal object of the invention is to provide a magnifying device for the warning signal which makes the same appear larger than it really is at certain distances.

A feature of the invention by which this object is attained consists in the provision of a lens having magnifying properties placed before the stencil. The stencil is so positioned as to be at the focal point of the magnifying portion of the lens and hence a sharp, clear and highly magnified image of the legend cut in the stencil is produced when the lamp bulb is lighted.

Another feature of the invention resides in the provision of a reflecting surface upon the stencil member positioned behind another portion of the lens for receiving and reflecting light rays therethrough. When the lens is made, as is usually the case, of red glass, the lights of an approaching car impinge upon this reflecting surface and are reflected thereby to produce the illusion of a lighted tail lamp.

Another feature of the invention resides in the provision of a second bulb within the lamp adapted to project rays of light through another portion of the lens for use as a common tail light.

Another feature of the invention resides in the provision of a shield member within the lens casing supported entirely by the socket of one of said lamp bulbs for confining the light from each of said lamps to the proper portion of the lens.

Other objects and features of the invention will be understood from the accompanying drawing and the following description and claim:

Fig. 1 is a central sectional view through the assembled lamp. Fig. 2 is a perspective view of the preferred form of stencil member having the faceted reflecting surface. Fig. 3

is a front elevational view of the preferred form of lens.

A lamp casing 10 has fastened thereto a member 11 carrying bolts 12 which may be secured to any suitable form of support. Within the said casing there is fastened a member 13 carrying an upper lamp socket 14 and a lower lamp socket 15. The socket 14 carries a lamp bulb 16 and the socket 15 carries a lamp bulb 17. A plug socket 18 projects through an opening in the casing 10 and is adapted to receive a plug, not shown, for transmitting electric current to the bulbs. A pair of electrical conductors 19 conduct the said current from the unit 18 to the sockets 14 and 15.

The casing 10 is open at one end in the usual manner and the said opening is surrounded by an inturned flange 20. Adjacent the flange 20 a shoulder 21 is formed upon the casing. A stencil member 22 shown particularly in Fig. 2 is positioned abutting the flange 20 and a lens 23 abuts the said stencil member. A door rim 24 serves to maintain the stencil and lens in place and is fastened to the casing 10 by means of a screw 25 or other suitable means. The lens 23 is formed with a circular central portion 26. A portion of the stencil member 22 positioned behind the said portion 26 is formed with a pyramidal depression 27, the inner surfaces of which are highly polished to provide for reflection of light impinging thereon. The pyramidal form of the portion 27 insures that there will be several reflecting surfaces at various angles so that light impinging thereon from any direction will be reflected in several different directions and will thus be distributed to be visible from any position behind the car. The lens 23 is preferably formed of red glass so that the reflection from the reflecting surface will give the illusion of a lighted tail light even though none of the bulbs are lighted. If desired, however, the lens may be of clear glass and a color filter may be interposed between the lens and the reflecting surface. It is not necessary that the portion 26 of the lens be in the form of a bull's-eye as shown in the drawing. It may be shaped as desired.

100

The lens 23 has formed about the central portion 26 an annular portion 28 having a convex outer surface and a concave inner surface. The radii of curvature of the two surfaces are different, as shown in Fig. 1, and this portion of the lens, therefore, serves to magnify any object placed adjacent thereto and in proper focus therewith. The portion of the stencil member 22 positioned immediately behind the upper part of the annular portion 28 of the lens has cut therein a legend 29 which may be in the form of a stop warning, an announcement of the make of the car, a trade-mark emblem or any other desired form. The said portion of the stencil member is outwardly bent as illustrated at 30 to bring the same into proper focus with respect to the magnifying portion of the lens. The bulb 16 is positioned immediately behind this portion of the stencil member and, when lighted, serves to project a magnified image of the legend carried thereby through the lens. The magnifying portion 28 of the lens may be formed with the inner surface flat rather than concave. In that case, the stencil may be placed flat against the lens and will be in focus when in that position.

The lower portion of the stencil member 22 adjacent the annular portion 28 of the lens has an opening 31 cut therein through which the light from bulb 17 may pass. The inner surface 32 of the lens adjacent the opening 31 is broken as illustrated in the drawing to provide diffusion of light from the bulb 17. The bulb 17 is normally kept lighted during the hours of darkness and serves as a common tail light. A clear lens 33 is set in an opening in the lower portion of the casing 10 adjacent the bulb 17 and serves for illumination of a number plate placed therebeneath. A shield 34 surrounds the socket 14, is supported thereby and serves to confine the light from bulb 16 to the upper portion of the lens and that from bulb 17 to the lower portion of the lens.

In the manufacture of the lamp as described, the forming of the stencil member with the pyramidal or faceted reflecting surfaces integral therewith is an important feature. While the stencil could be cut in one member and the reflecting surfaces placed in another, such a construction would require the bolting together of the two members or the provision of some separate form of support for the reflecting surface. By the construction herein shown, on the other hand, the expense and labor is greatly reduced.

In the foregoing description it has been assumed that the stencil member is of a thin metallic construction with the legend cut therein. However, the said member may be formed of glass or other transparent substance and may have the legend painted thereon with an opaque substance or de-

pressed in glass to provide a different degree of transparency to make the legend visible. If a transparent stencil plate is used the reflecting portion 27 is provided with a reflective coating of the usual mirror type. In the claim the word "stencil" is intended to include such constructions as these in addition to that herefore described.

The forming of the shield member 24 so that it may be supported directly upon one of the lamp sockets is also an important factor in reducing the expense of the construction.

The invention claimed is:

A lamp construction including a casing 30 having an opening therein, a lens closure for said opening having a convex outer surface for magnification, a lamp bulb within said casing, and a stencil interposed between said lens and said lamp, said stencil being shaped 35 in approximate conformity with the inner surface of said lens to bring the same into proper focus whereby a legend formed thereon will be magnified.

In witness whereof, I have hereunto affixed my signature.

HARRY C. FOSTER.
